UNITED STATES PATENT OFFICE

2,186,317

TELEPHONE SYSTEM

Charles Edmund Beale and Idris Trevor Richards, Liverpool, England, assignors to Associated Telephone & Telegraph Company, Chicago, Ill., a corporation of Delaware

Application March 26, 1938, Serial No. 198,223
In Great Britain April 13, 1937

11 Claims. (Cl. 179—27)

The present invention relates to telephone systems and is more particularly concerned with so-called automatic trunk exchange systems which employ automatic switches for the selection of trunk lines. The invention is particularly applicable to exchanges of the above type in which the trunk board operators are provided with digit keysets on which the number of the required trunk or group of trunks is set up. In response to this an impulse sender common to a number of operators comes into operation in a well-known manner on receipt of a start signal and sends out trains of impulses to set up the train of switches. A system of this general type is disclosed in British Patent No. 459,803. The object of the invention is to provide an improved key-operated impulse sender giving special facilities such as may be desirable in systems operating on the above described lines.

According to one feature of the invention in a telephone system employing automatic selecting switches for the selection of trunk lines under control of a key-operated impulse sender, arrangements are made whereby if delay working is in force on a desired group of trunks the sender withholds transmission of the keyed-up digits and returns an indication to the operator of the estimated time of delay. It should be explained that delay working represents the condition when owing to congestion on a particular route a supervisor has thrown a key or performed some similar operation to indicate to the operators that calls over that route cannot be completed on demand on a call storage basis but must be handled by a special delay operator.

The invention will be better understood from the following description of one method of carrying it into effect, reference being had to the accompanying drawings comprising Figs. 1-7. Fig. 1 is a trunking diagram showing in schematic form the trunking arrangements at a typical automatic trunk exchange while Figs. 2-7 which should be arranged in the manner indicated at the bottom of Fig. 5 to form one complete diagram, show the circuits of a seven-digit impulse sender with alternative routing and delay testing facilities. The two-motion switch employed in the sender is assumed to be of the two-magnet type as disclosed in the patent to Saxby No. 2,028,689, and has so-called rectangular motion, while the uni-directional switches employed are of the well-known reverse drive step-by-step type.

Considering first the trunking diagram, Fig. 1, automatic subscribers in the area local to the

trunk exchange obtain connection to the trunk exchange by dialling 0. In response to this a two-motion switch CCF terminating the incoming line ILL is caused to hunt for an idle demand operator's position DP. When an idle position is found, the connection is extended over the connecting circuit CC and the position circuit PC and the operator speaks to the calling party, records particulars of the call and then operates a key in order to connect with a first selector 10 which on seizure engages a free sender S over a hunting switch SH.

It will be seen that access can be had to the train of trunk selecting switches S1, S2 and S3 only over the 0 level of the first selector S1, the other levels of this switch extending by way of outgoing relay sets such an OGR to the local metropolitan automatic exchange. The first, second and third selectors S1, S2 and S3 respectively are of the two-motion type, the switches S3 having direct access to groups of outgoing trunk lines and being of the two-digit type, that is to say, the first digit received serves to select a group of trunks and the second digit determines whether hunting shall take place or whether an individual trunk in the group shall be selected. Four digits must therefore be keyed up to obtain access to a group of trunks and 0 must be keyed as a first digit. The third selector may have facilities for call storage as described in our pending application No. 193,414, filed March 2, 1938, or alternatively they may have facilities for repeating testing of a trunk group until a free trunk is found as described in our pending application No. 193,415, filed March 2, 1938.

The operator now keys up the routing digits required by means of the keyset KS and if a trunk connection is to be set up, 0 is keyed as a first digit whereupon a circuit change is brought about in the sender so that after the keying up of the second and third digits in the number to select a particular group of trunks, an auxiliary switch AS in the sender is caused to search for markings applied to one of its banks in accordance with these latter digits. This auxiliary switch is of the 100-outlet two-motion type and when it has thus positioned itself access can be had over its wipers to a group busy equipment such as GBE associated with the desired group of trunks, to a group busy equipment associated with a group of trunks which provide an alternative route to the desired distant exchange if such a route is available, and also by way of these group busy equipments to the delay supervisor's position DS. Before the sending out

20

25

30

35

40

45

50

of the keyed-up digits commences, simultaneous tests are made on both the regular and alternative routes and if the regular route is free and delay conditions are not obtaining thereon, the keyed-up code is at once sent out while if it is engaged or in delay the alternative route is tested if one is provided. If the alternative route is free and not in delay, the alternative route code as determined by the setting of other wipers of the auxiliary switch is sent out but if it is busy or in delay or such a route is not provided the call is routed over the regular route even if this latter route is engaged but not if it is in delay. If the third selector is of the call storage type, the call will then be placed in storage while if this switch is of the re-searching type it will perform repeated testing operations until a trunk in the group becomes free. If however delay conditions are in force on the regular route, no sending takes place and a tone signal is returned to the operator indicative of the estimated time of delay.

In the case of calls incoming over a trunk line such as ITL to the through position TP at which the equipment is substantially the same as that at the demand position, the first digit keyed may be other than 0 in order that an incoming call from a distant exchange may be routed to the local metropolitan automatic exchange. Since the first digit is other than 0, the auxiliary switch in the sender is not set into operation as it is not required and the keyed-up code is therefore sent out as soon as the operator depresses her start key.

Referring now to Figs. 2-7, the detailed circuit operation of the sender will be described. On the seizure of the sender equipment, earth applied by way of a relay in the first selector over the SW lead operates relay SW, Fig. 5, which thereupon operates relay B, Fig. 6, over its lower winding. Relay B at armature b_1 earths a common operating and holding lead 15, at armature b_2 , Fig. 5, returns a guarding and holding earth over the incoming P conductor and at armature b_4 , Fig. 3, extends an earth from wiper DD1 in position 1 to energise the distributor switch magnet DDM, Fig. 5, in series with relay BP, Fig. 6, the function of which will be dealt with later in the description. The magnet now interacts with its interrupter contacts dm to advance the wipers to position 2 where relay BA is operated by way of its left-hand winding from the same wiper and bank. This relay at armatures ba_1 and ba_2 , Fig. 2, inserts relays DSA and DSB in the incoming keying conductors -IN and +IN which extend over the wipers DD3 to DD6 in position 2 to relays AW, AX, AY and AZ which comprise the first set of decoding relays. It should be explained that keying is effected from the operator's position circuit over two wires by combinations of positive pulses and light and heavy negative pulses, and at the receiving end these pulses are directed into the appropriate one of the available four channels by the use of the metal rectifiers MRA, MRE, MRC and MRD; this method is described in detail in British Patent No. 398,812. Relay BA also at armature ba_5 , Fig. 7, earths a common operating and holding lead 16 and lights the sender engaged lamp LP, and at armature ba_6 it locks over its right-hand winding.

Assuming that the sender is seized from a demand operator's position and that the number keyed is 0831, on the depression of the digit key 0 a light negative impulse is sent over the incoming positive keying lead and at the same time a posi-

tive impulse is sent over the incoming negative lead. The circuits extend by way of relays DSA and DSB, rectifiers MRB and MRC in conductive directions and wipers DD4 and DD5 in position 2 and serve to operate relay AX over its right-hand winding and relay AY over its right-hand winding in series with the middle winding of relay AZ, relay AZ not operating in these circumstances due to the light nature of the pulse. Relays AX and AY thereupon lock over their left-hand windings to lead 15 and prepare a marking corresponding to the digit 0 in the bank S4 of the sending switch S in a manner to be described. Earth is also extended from lead 15 over armatures ax_5 , ay_5 and az_6 to operate relay TG over its upper winding. This relay thereupon locks over its lower winding at armature tg_1 to the earthed lead 16, prepares a self-driving circuit for the vertical magnet VM, Fig. 7, of the auxiliary switch at armature tg_3 and at armature tg_5 , Fig. 6, disconnects an operating circuit for the sending start relay SS which would otherwise be completed when the operator subsequently depressed the start key after the keying of the fourth digit in the number. By this arrangement the sender cannot start sending out until both the operator's start signal and a signal from the auxiliary switch are received. Meanwhile the series connected relays DSA and DSB are also operated due to the depression of the digit key 30 and energise the magnet DDM, Fig. 5, of the distributor switch over armatures dsa_1 and dsb_1 . On the release of the key these relays restore and de-energise the magnet DDM which thereupon advances the wipers of the switch DD into position 3.

The key 8 is next depressed and this results in the connection of a light negative pulse to both of the incoming keying conductors where it finds a path by way of the series connected relays DSA and DSB and rectifiers MRA and MRC. Accordingly circuits are completed for relays BW and BX and BY and BZ in series but due to the light nature of the pulse, relays BW and BY alone operate. These two relays thereupon lock and prepare a marking corresponding to digit 8 in the bank S4. When key 8 is released, the DD switch wipers are advanced to position 4 in the manner described above.

On the depression of the digit key 3, a heavy negative pulse is applied to the negative keying conductor and this finds a circuit by way of rectifier MRA to bring about the operation of relays CW and CX in series. These two relays lock in the usual manner and prepare a marking corresponding to digit 3 in the bank S4. On the release of key 3 the DD switch wipers are advanced to position 5.

The advancement of the DD switch wipers to the fifth position indicates that the required group of trunks has been selected, the fourth digit which is to follow merely determining whether hunting shall take place over the whole or part of the selected group or whether a particular trunk in the group is to be selected. The two-motion switch is therefore now caused to search for vertical and rotary bank markings made in accordance with the digits keyed into the sender.

Earth is now extended from the busy key contacts KB1, Fig. 7, over armatures ba_5 , ck_5 , co_1 , do_3 and tg_3 , wiper DD2 in position 5 and armature h_4 to operate relay FS by way of its lower winding in series with magnet RM and relay BP which do not however operate in this condition. Relay FS upon operating locks over its upper

winding by way of its armature $fs1$ and completes a self-interrupted driving circuit for the vertical magnet VM from earth extended by way of its armature $fs2$ and armatures $pa1$, $h1$ and $rs2$, 5 vertical magnet interrupter contacts vm , and magnet VM to battery via relay BP and accordingly the wipers are raised vertically step-by-step. Relay FS also at armature $fs3$, Fig. 3, extends a battery marking potential by way of armatures of 10 the second set of decoding relays which have been operated to the left-hand vertical bank VB of the two-motion switch and since in this case relays BW and BY have been operated in response to the second digit 8 the battery marking potential is 15 applied over armatures $bw2$, $bx2$, $bz2$ and $by3$ to contact 3 in the vertical bank VB.

When the vertical wiper VW encounters this marking, relay PA operates quickly and opens the magnet driving circuit at armature $pa1$ and at 20 the same armature completes an operating circuit for relay RS. This relay thereupon locks over its "make-first" light armature $rs1$, at armature $rs2$ further disconnects the vertical magnet driving circuit and prepares a driving circuit for 25 the rotary magnet RM, at armature $rs3$ short-circuits and thus releases relay PA, Fig. 4, at the same time connecting this relay to the test wiper P in preparation for the rotary search, disconnects the resistance marking battery from 30 the contacts of the second set of decoding relays at armature $rs4$, Fig. 3, and extends it over armature $rs5$ to the contacts of the third set of decoding relays in order that the position of the desired trunk group can be marked in the bank of 35 wiper P.

It should be mentioned that the corresponding contacts on each of the levels of this bank are multiplied together, a lead extending from each of the ten sets of multiplied contacts in the bank 40 to the armatures of the decoding relays so that in this case since relays CW and CX are operated in response to the keying of digit 3 the third contact on each level will be marked from the resistance battery YB by way of armatures $fs8$, 45 $rs5$, $cw2$ and $cx2$.

On the release of relay PA, a self-interrupted driving circuit is completed for the rotary magnet RM from earth by way of armatures $pa1$, $h1$ and $rs2$, fault release jack FRJ, off-normal contacts N2 which were mechanically operated on the 50 first vertical step of the auxiliary switch, rotary magnet interrupter contacts rm , rotary magnet RM to battery via relay BP and the wipers are accordingly rotated in search of the marking.

On the first rotary step the rotary off-normal 55 springs are mechanically operated and at contacts NR1, Fig. 4, relay PA is disconnected from the vertical bank, at contacts NR2, Fig. 7, relay RS is disconnected but remains held over wiper and bank DD2 and at the same contacts an operating circuit is prepared for relay H while at contacts NR3, Fig. 4, the short-circuiting earth is removed from relay PA.

When the P wiper encounters the marking, 60 relay PA again operates to open the magnet driving circuit and this time it operates relay H. Relay H thereupon further opens the magnet driving circuit at armature $h1$, prepares a circuit for the sending start relay SS, Fig. 6, at armature $h3$, completes a locking circuit for itself over its armature $h4$ and also releases relay RS which in turn releases relay PA. If the operator has 65 not already depressed the sending start key, no further operation takes place until she does 70 so, while if this key has already been depressed

relay SS will now operate and initiate the sending out of the stored digits unless it is found that delay conditions are obtaining on the desired trunk group, as will be described later.

In the meantime the fourth digit 1 of the required number will have been keyed up and in response to this a light negative pulse is transmitted over the incoming negative conductor to operate relay DW. This relay locks and prepares a marking corresponding to digit 1 in the bank of wiper S4 and at armature $dw3$, Fig. 6, extends an earth over armatures $dy5$, $dz1$, $dx6$ and $tg4$ to operate relay AR the purpose of which will be described later. On the release of the key, the DD switch wipers are advanced in the normal manner to position 6.

Since the four digits corresponding to the required number have been keyed up, the operator now depresses the sending start key which effects the connection of a light negative pulse to the negative keying lead and a heavy negative pulse to the positive keying lead. In response relays EW, EY and EZ are operated over the DD3 and DD5 wipers in position 6 and prepare a circuit over armatures $ew2$, $ex2$, $ez2$ and $ey4$, Fig. 6, for the cut-off relay CO which is operated after the subsequent transmission of the setting digits. If in the meantime relay H has been operated thereby indicating that the two-motion switch has completed finding, an operating circuit will be completed for relay SS from the earthed lead 15 by way of armatures $ew3$, $ey5$, $ez6$, $ex5$, and $h3$ to initiate the transmission of the decoded digits.

It will be appreciated that the cut-off circuit and start circuit described could be prepared equally well by the operation of a similar combination of relays in any of the seven decoding sets if a different number of digits had been keyed. If however, the full seven digits are keyed relays HX and HW are utilised to respond either to a start signal, or in a manner to be described later, to a cancel signal.

Relay SS upon operating, at armature $ss1$, Fig. 6, prepares an operating circuit for relay IG and at armature $ss2$, Fig. 7, disconnects the holding circuit for relay FS which holds operated for a further short period due to its slug. At armatures $ss5$ and $ss6$, Fig. 5, the incoming keying leads are disconnected and at armature $ss7$, Fig. 6, earth is connected up over the CN2 wiper in position 1 to the armatures of the first set of decoding relays. During the release time of relay FS the lower winding of relay GE, Fig. 7, is connected over armatures $ss3$, $dr1$ and $fs3$ to the wiper R of the two-motion switch while the upper winding of relay AGE is connected over armatures $ss4$, $dr2$ and $fs4$ to wiper A. The banks of these wipers and also of wipers D1, D2 and RD are multiplied to the corresponding banks of the two-motion switches of other senders and extend to the various trunk group busy equipments while banks C1, C2 and P of the two-motion switch are wired individually in each sender. The R, D1, D2 and RD bank contacts on which the wipers are now positioned extend to a group busy equipment associated with the trunk group 083 and if there is an alternative route provided to the desired exchange the bank contact on which the A wiper is positioned extends to a group busy equipment associated with this route. If there is no alternative route provided, the A bank contact is permanently earthed in the sender by way of the strap connection shown dotted. If the trunk group 083 serving the so-called regular route is engaged

or in delay, wiper R will encounter an earth point 75

tential extended from the associated group busy equipment and if the alternative route is engaged or in delay wiper A will also encounter earth.

It will first be assumed that the regular route 5 is neither engaged nor in delay, in which case the R wiper will not pick up any potential and relay GE will not therefore be operated. On release of relay FS, the sender therefore will commence to send out trains of pulses corresponding 10 to the digits keyed in a manner to be now described and the call will be routed over the regular route. The operation of relay AGE due to the alternative route being either engaged or in delay is without effect in the above condition.

15 Relay FS on releasing completes a holding circuit for relay B over its upper winding at armature $fs6$, Fig. 6, the lower winding of the latter relay being subsequently disconnected on release of relay SW when the first selector switches 20 through to the second selector while at the same armature earth is extended to relay IG and to the motor-driven magnet impulse springs MIS. Relay IG, the function of which is to prevent the extension of a clipped impulse from the impulse 25 springs MIS to the sending switch driving magnet SM, does not operate until the impulse springs open and when it does so it connects them up at armature $ig1$ to the magnet SM. Accordingly the sending switch wipers are advanced step-by-step 30 round the bank contacts and it will be noticed that as soon as wiper $S2$, Fig. 5, reaches position 3 the loop impulse springs LIS which are operated from the same motor as the magnet springs MIS and which are closed during such time as 35 the magnet springs are open and vice versa, are connected across the -OUT and +OUT conductors extending to the first trunk selector so that on each subsequent step of the sending switch an impulse is delivered to the selector.

40 When ten impulses corresponding to the first digit keyed have been delivered to the first trunk selector, wiper $S4$ will pick up an earth supplied to contact 13 by way of the central switch wiper CN2, Fig. 6, in position 1 and armatures $aw2$, 45 $ay2$ and $ax4$, Fig. 4, whereupon relay SZ, Fig. 7, operates and locks by way of armature $s21$ and the $S3$ bank and wiper to earth. Relay SZ disconnects the loop pulse springs LIS from the outgoing loop at armature $s26$ and replaces them 50 by the winding of relay D, at armature $s22$, Fig. 6, opens the pulsing circuit to the magnet SM and disconnects relay IG which is slow in releasing due to its slug and at armature $s24$ completes a circuit for the control switch magnet CNM. 55 During the release time of relay IG, earth is extended over the $S1$ wiper and bank and armatures $ig3$ and $s21$ to operate relay PC over its lower winding whereupon at armature $pc1$ the upper winding of this relay is inserted in the outgoing loop in order that it may hold operated when relay IG releases.

On the release of relay IG, the timing of a suitable interdigital pause commences but in addition arrangements are provided by which the 60 length of this pause can be automatically adjusted in accordance with the actual time taken for a selector which has just been set to hunt for and switch through to a succeeding selector. It will be noticed that on the release of relay IG 65 the lower winding of relay PC is disconnected at armature $ig3$ and this relay now holds on its upper winding which has only sufficient turns to produce a suitable holding flux. When the first selector completes its hunting operation and 70 switches through, there is a momentary interrup-

tion of the loop current which allows relay PC to release due to the inefficiency of its holding winding and it thereupon at armature $pc1$ short-circuits its upper winding to prevent re-operation when the loop current is restored and completes a self-interrupted driving circuit for the magnet SM from earth over the $S1$ wiper and bank, armatures $s23$, $pc2$, $ig2$, and $ig3$, magnet interrupter contacts sm , magnet SM to battery via relay BP so that the S switch wipers are restored quickly to the home position 1. The sending out of the next digit then commences.

Should relay PC fail to respond to the transient signal or should there be no signal returned as would occur between the two digits during the 15 setting of a standard type of final selector switch, the normal interdigital pause will be provided in the following manner. On release of relay IG the impulse springs MIS are again connected across its winding and a self-interrupted driving circuit 20 is completed at armature $ig3$ for the magnet SM from bank and wiper $S1$. After wiper $S1$ has advanced beyond contact 19 , the self-interrupted driving circuit is disconnected and earth is re-connected to the winding of relay IG over armatures $s23$ and $pc2$ and when this relay re- 25 operates on the opening of the magnet impulse springs MIS, the sending switch is stepped over the next group of contacts under control of these springs so that a predetermined period may be 30 timed. When wiper $S1$ advances beyond contact 23 , relay IG is released and a self-driving circuit is again completed for the magnet SM so that the switch S quickly rotates to the home 35 position 1.

When the switch reaches this position, relay SZ releases and de-energises the control switch driving magnet CNM which thereupon advances the wipers to position 2. Wiper CN2 now extends an earth to the armature of the second set 40 of decoding relays. The original operating circuit is again completed for relay IG at armature $s22$ and the sending switch S again commences to step under control of the impulse springs MIS to send out a train of eight impulses corresponding to the second digit keyed in the same manner as the first train except that the wiper $S4$ on reaching position 11 will encounter a marking 45 extended over armatures $gr1$, $fs3$, $rs4$, $bw2$, $bx2$, $bz2$ and $by3$.

After the transmission of this digit, the CN wipers are advanced to position 3 and the third train of three impulses corresponding to the third keyed-up digit 3 is then sent out, the marking being extended over armatures $gr2$, $rs5$, $bw2$ and 55 $bx2$ to position 6 on the $S4$ bank.

Before the sending of the fourth digit is described, one or two points in connection with the setting of the two-digit third selector in the trunk selecting train will be dealt with. If 0 60 is keyed as the first digit, thereby indicating to the sender that the trunk selecting train is to be utilised, it is arranged that if the fourth digit keyed is 1 an unbalance signal is transmitted in response instead of an impulse. It will be 65 understood from the description of the third selector in our pending applications Nos. 193,414, and 193,415, filed on March 2, 1938, previously referred to that by this arrangement the first outlet of each level need not be wasted as would 70 be the case if an impulse was transmitted. On reception of this unbalance signal the third selector taken into use is caused to perform a hunting operation over the whole of the selected trunk group.

As mentioned previously, in response to the keying up of the fourth digit 1 relay DW is operated and operates relay AR. This relay thereupon at armature *ar*, Fig. 5, prepares a circuit for unbalancing the outgoing loop after transmission of the third digit and at armature *ar2* prepares a circuit for quick-stepping the CN switch wipers past the position 4 which they would normally occupy for the sending of the fourth digit. During the sending out of the third train of impulses the CN switch wipers are in position 3 and hence on operation of relay SZ at the end of the train an earth will be applied over wiper CN1 and armatures *ar1* and *ss2* to unbalance the outgoing loop. This earth also short-circuits and releases relay PC since the outgoing positive loop conductor connects with the earthed winding of the distant impulsive relay and the sending switch S is therefore quickly self-driven to the home position. When relay SZ releases on completion of the homing of the switch S, the switch magnet CNM is de-energized and the wipers are thereby advanced to the next position 4 which would be normally occupied during the sending out of an ordinary fourth digit. Since no fourth digit is sent out however a circuit is completed from the earthed wiper CN1 in this position over the operated armature *ar2* to quick-step the wipers to position 5. In this position earth is extended over wiper CN2, Fig. 6, and armatures *ew2*, *ew1*, *ez2* and *ey4* to operate relay CO which then locks over its armature *co2* and at the same armature removes the holding earth from lead 15 thereby releasing the decoding relays and relays B, SS and AR while at armature *co1*, Fig. 7, the holding earth for relay H and for the relays associated with the two-motion switch wipers is removed. The release of relay AR at armatures *ar1* and *ar2*, Fig. 5, prepares a homing circuit for the control switch CN while the release of relays H and SS initiates the homing of the two-motion switch by the completion of a self-interrupted driving circuit for the rotary magnet RM from earth over armatures *ss1*, Fig. 6, *fs1* and *h2*, fault release jack FRJ, off-normal contacts *N2*, rotary magnet interrupter contacts *rm*, magnet RM to battery via relay BP and the switch wipers are accordingly advanced to the 12th position whereupon they restore vertically under gravity and then rotate under spring control back under the banks to their full normal position where the magnet driving circuit is opened by the off-normal contacts *N2*. On the release of relay B after its slow release period, the holding circuit for relay CO is disconnected at armature *b1* but this relay does not release for a short interval due to its slug. Relay BA, Fig. 3, is also released at the same armature. At armature *b2*, Fig. 5, the guarding and holding earth is removed from the incoming P conductor but the sender will still remain marked as engaged until the idle marking battery is replaced on this lead. Relay B also at armature *b5*, Fig. 3, completes a self-interrupted driving circuit for the distributor switch magnet DDM from the earthed wiper and bank DDI, armature *b5*, magnet interrupter contacts *ddm*, armature *ck1*, magnet DDM to battery via relay BP and the switch wipers are accordingly rotated to a home position 13 where the driving circuit is opened. The next time the sender is taken into use the DD switch will start from this position and then subsequently restore to its other home position 1. On the release of relay BA, relay TG, Fig. 6, is released at armature *ba5*,

Fig. 7, and at the same armature the sender supervisory lamp LP is extinguished, while at armature *ba3*, Fig. 5, a homing circuit is completed for the control switch CN and the wipers are thereupon rotated to position 1. When all switches have reached their home position and relay CO has released, the idle marking battery is replaced on the incoming P conductor by way of resistance YA, armatures *ba4* and *b1*, off-normal contacts *N1*, armature *co3*, key contacts KB4 and armature *b2*, so that the sender is now marked as free for further use.

Cancellation of the keyed-up digits may be effected at any time prior to the operation of the start key by the operation of the cancel key in the position circuit. This results in the connection of a heavy negative pulse to both of the incoming keying conductors and accordingly all the decoding relays of whichever set is then connected up are operated. Relay CK, Fig. 5, is therefore operated over its lower winding and at armature *ck1* inserts its low resistance upper winding in the circuit of the distributor switch magnet DDM and at armature *ck2*, Fig. 3, completes a self-interrupted driving circuit for this magnet in order to home the distributor switch. At armatures *ck3* and *ck4* the incoming keying leads are opened, at armature *ck5*, Fig. 7, the holding earth for relay TG and other relays is disconnected, while at armature *ck6* Fig. 4, the holding earth lead to the decoding relays is disconnected. During the homing of the DD switch relay CK remains held over its upper low resistance winding and when the switch reaches the home position relay CK releases and restores the circuit conditions in readiness for the keying-up of the correct digits.

Returning to the point in the description where relays GE and AGE were connected to wipers R and A, it will now be assumed that the regular route is either engaged or in delay and that an alternative route is available which is not in delay. Furthermore it will be assumed for a reason to be described that the fourth digit keyed is 1. During the release time of relay FS relay GE will be operated by an earth extended over the R wiper from the regular route group busy equipment, but since the alternative route is free and not in delay the A wiper will encounter no earth and hence relay AGE will not operate. Relay GE locks over its upper winding at armature *ge1* and at armature *ge3* operates relay GR. This relay at armatures *gr1* and *gr2*, Fig. 3, disconnects the regular route markings corresponding to the second and third digits keyed and connects up in place a two-digit alternative route code which is effected over leads 17 and 18, wipers and banks C1 and C2 of the two-motion switch and a suitable translation field TF. For example the first three digits of the keyed up number 0831 might be changed to 065; the last digit 1 being sent out in a normal manner as an unbalance signal so as to initiate hunting over the whole of the alternative route group of trunks.

If however the fourth digit of the number is other than 1, thereby indicating that it is desired either to select a particular high grade trunk in the group comprising the regular route, or to cause hunting over a sub-group of trunks therein, the aim of the operator would be defeated if the call was routed over an alternative route. Accordingly it is arranged that if relay AR is not operated, that is to say, if 1 is not keyed up as a fourth digit, relay AGE is operated over its

lower winding as soon as relay SS operates and this simulates the effect of an engaged or in delay condition on the alternative route so that the call will not be routed thereover if the regular route is either engaged or in delay.

If both the regular and alternative routes are found to be busy, both relays GE and AGE are operated, so that relay GR is not operated whereupon if the regular route is not in delay, the keyed-up code is sent out over this route. The call will then either be placed in call storage by the third selector or alternatively if another type of third selector is used the trunk group will be hunted over repeatedly until a free group is found.

If the regular route group is in delay and if the alternative route cannot be utilised, that is to say, it is also in delay or engaged, relays GE and AGE will be again operated. During the release time of relay FS the lower winding of relay DR is connected over armatures *age4* and *fs5* to the wiper RD which due to the delay condition will encounter earth extended from the group busy equipment associated with the group of trunks serving the regular route. Relay DR therefore operates and locks over its upper winding at armature *dr3*, at the same armature disconnects the locking circuits of relays GE and AGE, at armatures *dr1* and *dr2* connects the lower windings of these two relays to the D1 and D2 wipers respectively, at armature *dr4*, Fig. 5, connects the retard TR across the incoming keying conductors in order that tone signals may be returned to the operator and at armature *dr5*, Fig. 6, disconnects the earth supply to relay IG so as to prevent the sending out of the keyed-up digits. It is arranged that the contact on which the D1 wiper is resting is earthed from the group busy equipment associated with the regular route as soon as delay conditions are put in force thereon by the delay supervisor. If the supervisor wishes to signal that there will be an estimated delay of twenty minutes as would be determined from the number of dockets she is holding she will operate a so-called twenty minute delay key. If the delay is likely to be of the order of forty minutes she throws another key and the contact on which wiper D2 is resting will be earthed instead of that engaged by wiper D1 while the earthing of the contacts engaged by both wipers D1 and D2 will indicate a delay of sixty minutes. Accordingly therefore if the delay is of the order of twenty minutes relay GE will be operated over the D1 wiper whereupon a tone is extended over common lead 11, Fig. 5, and armatures *age2* and *ge2* to the right-hand winding of the retard TR, this tone then being induced in the left-hand winding and extended on to the incoming keying conductors in a balanced circuit. The operator is thus notified and will then inform the calling subscriber of the approximate waiting period, and will release the sender and forward the docket recording particulars of the wanted connection to the delay supervisor. If the delay is of the order of forty minutes, relay AGE will be operated and a different tone signal will be connected to the winding of relay TR from common lead 12 while if the delay is of the order of sixty minutes, both relays GE and AGE will be operated to connect up another tone indication from common lead 10 to the right-hand winding of retard TR.

The case will now be considered in which the sender is taken into use by an operator at a through position who wishes to extend an incoming call to a local automatic exchange. In this

case the first digit keyed will be other than 0 and hence relay TG will not be operated so that the two-motion switch is not started up to find a marking since it has no function on this class of call. On receipt of the start signal, trains of pulses in accordance with the digits keyed are therefore immediately sent out to route the call to the required destination. Furthermore under this condition since relay TG is not operated relay AR cannot be operated in response to a fourth digit 1 so that if this digit is keyed it will not be converted into an unbalance signal.

If in the setting up of a call any selector in the train, excepting the third trunk selector, finds all outlets on a level busy, arrangements are made to return a signal to the sender so that it may immediately release and drop out of the connection; at the same time the originating key-sending operator receives busy tone without having to wait until the sender has finished sending. Assuming for example that the second selector finds all outlets busy, it rotates to the 11th step and thereupon connects positive battery to the PS lead. This extends by way of armature *co4* and rectifier MRE in a conductive direction to operate relay ZR over its left-hand winding, the rectifier MRE preventing the extension of an earth potential by way of this winding on to the PS lead which might bring about false operation in the selecting switches. Relay ZR at armature *zr1* locks over its right-hand winding to lead 16, at armature *zr2*, Fig. 6, operates relay CO to bring about the release of the sender and at armature *zr3* breaks the circuit for relay SW. It will be understood that this relay is held operated during the setting and hunting operation of the first selector only, and if this switch encounters a busy condition the operation of armature *zr3* avoids the possibility of relay B being held on its lower winding from armature *sw1* and thus maintaining an earth on the P-lead which would bring about a lock-up between the sender and this selector. On the release of relay B in response to the disconnection of its holding circuit at armature *co2*, the guard and holding earth is removed from the P-lead whereupon the first trunk selector extends its incoming leads through to the second selector. Busy tone is thereupon transmitted from this selector by way of the first selector to the operator.

When delay working is introduced on any of the trunk groups, an operator is assigned to clear up the waiting dockets. Arrangements are provided whereby she may use an ordinary position from which she may gain access to a group in delay. For this purpose a simple strapping connection is effected in the position circuit while a "delay operator" key is thrown, the strapping preventing unauthorized use of the "delay operator" key. When the sender is seized from such a position, in addition to the normal circuit operation, a momentary loop signal is extended forward over the keying conductors and this brings about the operation of relay DO, Fig. 2 from earth applied to the positive conductor by way of the distributor switch wiper *DD5* in normal position, this earth extending over the loop and back via the negative conductor to operate relay DO over its left-hand winding. Relay DO thereupon locks over its right-hand winding to lead 15 by way of armature *do1*, at armature *do2*, Fig. 6, prepares an operating circuit for relay SS which is independent of the armatures of relays H or TG and also at armature *do3*, Fig. 7, prevents the starting up of the two motion switch if the delay

operator should key 0 as a first digit. No matter what digits are keyed therefore, the sender will send out corresponding trains of pulses immediately on depression of the start key.

- 5 It will be noticed that on a call to a local automatic exchange, that is to say where relay TG is not operated, during the release of the sender a positive battery potential is applied by way of resistance YC, Fig. 5, to the PS lead.
- 10 This arrangement is provided so that during the transmission of trains of pulses a straight-through connection may be provided in the outgoing relay set to the automatic exchange in order to eliminate impulse repetition, while at 10 a
- 15 the end of the impulsion the momentary application of the positive battery signal over the PS lead will bring about the insertion of the well-known D and I supervision bridge in this relay set, so that the loop supervision from the automatic exchange may be converted to the sleeve supervision of the trunk board.

- Relay D is provided so that if at any time a double or extended hunting operation is required between switching stages, the sending out may 25 be held up beyond the normal interdigital pause. In such a case battery will be reversed over the negative and positive OUT leads to the sender until such time as the hunting operation is concluded and during this time relay D will be 30 operated since the rectifier MRF will be in a non-conductive direction. At armature $d1$, Fig. 6, the circuit for relay IG and the magnet impulse springs MIS is opened and the sending out of the trains of impulses is therefore held up 35 until relay D restores.

- If the sender is taken into use and not released after a predetermined period, the time delay relays TA and TB, Fig. 5, are operated to provide suitable alarms. When the sender is taken into 40 use, relay BA at armature $ba4$ connects battery by way of resistance YA to the upper winding of relay TA. The S and Z leads extending from the upper windings of relays TA and TB are common to a plurality of senders and connect 45 with a timing mechanism. If this mechanism is in its normal position it will extend on earth on to the S lead and assuming that this is the case relay TA will be operated and lock over its lower winding by way of armatures $ta1$, $tb1$ and 50 $bp2$ to the earthed holding lead 16. Relay TA at armature $ta2$ applies earth to the common start lead ST which it will be understood sets the timing mechanism into operation while at armature $ta3$ the upper winding of relay TB is 55 connected to the Z lead. On the setting into operation of the timing mechanism the earth is removed from the S lead so that the TA relay is connected to the S lead during the timing of the 60 predetermined period and after this period has elapsed the mechanism connects earth to the Z lead. This causes the operation of relay TB which thereupon locks over its armature $tb1$ and at the same armature releases relay TA. At 65 armature $tb2$ the battery potential to the upper winding of relay TA is disconnected to prevent re-operation of this relay when the timing mechanism restores to normal as a result of the removal of the earth from the ST lead, at armature $tb2$, Fig. 6, earth is applied to common lead 13 to operate an alarm in the exchange; while at armature $tb4$, Fig. 7, an interrupted earth is connected over common lead 14 to flash 70 the sender supervisory lamp so as to bring to 75

the notice of the exchange maintenance officer which particular sender is faulty.

Considering now the function of relay BP, Fig. 6, which is connected in the battery feed to all the switch driving magnets, if any switch should fail to home this relay will be maintained operated and at armature $bp1$, Fig. 5, opens a point in the idle test circuit and connects up relay TA to the timing mechanism while at armature $bp2$ a holding earth is provided for the relays TA and TB. Hence if relay BP is still operated at the end of the predetermined time interval an alarm will be given in the manner described in the previous paragraph and the taking into use of the sender will be prevented.

Should it be required to cut the sender out of service temporarily for test purposes, the busy key KG will be operated whereupon at contacts KB1, Fig. 7, the sender supervisory lamp LP is lit and at these contacts, contacts KB2, Fig. 7, and contacts KB3, Fig. 6, the earth is removed from the various holding leads in the sender so that any relays already held operated are released. On the release of the relay B, a guard earth is applied to the incoming P conductor 25 over key contacts KB4 and armature $ba4$.

We claim:

1. In a telephone system, trunk lines for extending calls over one or more routes, automatic switching equipment for controlling the extension of said calls, means for marking, in said equipment, those routes which are congested and have calls waiting, said marking for each congested route varying in accordance with the probable time required to complete said waiting calls and obtain a free trunk line in said route, a calling station, means at said calling station for seizing said equipment to extend a call over one of said routes and for transmitting to said equipment call-directing digits, and means in 30 a said equipment, effective if said one route is congested and has calls waiting, for automatically apprising the calling party of the probable length of delay before his call can be completed.

2. In a telephone system, trunk lines for extending calls over one or more routes, automatic switching equipment for controlling the extension of said calls, means for characterizing, in said equipment, those routes which are congested by heavy traffic and the degree of said congestion, 50 means for seizing said equipment for the extension of a call over one of said routes and for transmitting thereto call-directing digits, and means in said equipment, effective if said one route has been characterized as congested, for 55 signalling the calling party accordingly, different signals being reverted in accordance with the degree of congestion.

3. In a telephone system, trunk lines for extending calls over one or more routes, a calling station, automatic switches over which said trunk lines are accessible to said station, means for transmitting call-directing digits from said station to gain access, via said switches, to a trunk line in a particular route, signalling equipment 60 having means controlled by said digits, and means for characterizing, in said equipment, those routes over which calls may not be completed without delay, said characterization varying in accordance with the probable length of said delay, said signalling means effective, if said particular route is characterized, to signal the calling party to apprise him of the delay and the probable length thereof.

4. In a telephone system, trunk lines for ex- 75

- tending calls over one or more routes, a calling station, automatic switches over which said trunk lines are accessible to said station, means for transmitting call-directing digits from said station to gain access, via said switches, to a trunk line in a particular route, a register controlled by said digits, a switch controlled by said register and positioned in accordance with certain of said digits, means operated over the wipers of said last switch if calls may not be completed without delay over said particular route, said last means being operated variably in accordance with the probable length of delay, and means controlled by said last means to notify the subscriber of the probable length of said delay.
5. A telephone system as claimed in claim 4, wherein said switch is rendered effective only when one of the digits received by said register is of a predetermined value.
20. 6. In a telephone system, trunk lines for extending calls over one or more routes, a calling station, automatic switches over which said trunk lines are accessible to said station, means for transmitting call-directing digits from said station to gain access, via said switches, to a trunk line in a particular route, and means controlled by said digits for determining whether the call may be completed over said particular route without delay and, if not, for determining the probable length of the delay, said last means thereupon effective, if said call may not be completed without delay, to automatically notify the calling party of the delay and the probable length thereof.
25. 7. A telephone system as claimed in claim 6, wherein said last means is effective, only if said call may be completed without delay, to transmit impulses to said switches thereby controlling certain of the same to give the calling station access to a trunk line in said particular route.
30. 8. A telephone system as claimed in claim 6, wherein said last means includes sources of different tones and means selectively controlled in accordance with the probable length of delay for reverting to the calling party a particular one of the tones.
35. 9. In a telephone system, trunk lines for extending calls over any of a plurality of routes, certain of said routes being alternative routes for others of the routes, a calling station, automatic switches over which said trunk lines are accessible to said station, means for transmitting call-directing digits from said station to gain access, via said switches, to a trunk line in one route, a register controlled by said digits, means asso-

ciated with said register for determining the condition of said one route and, at times, of an alternative route, means for at times thereupon transmitting impulses to control said switches in accordance with said determination, and means effective at times if said call cannot be extended over either said one route or said alternative route without delay for determining the probable length of said delay and for signalling the calling party in accordance with the probable length thereof.

10. In a telephone system having trunk lines arranged in direct and alternative routes, a calling station, automatic switches over which said trunk lines are accessible to said station, a register sender for controlling said switches, means for transmitting call-directing digits from said station to control said register sender, means associated with said register sender effective first to determine the condition of trunk lines in a particular direct route and the corresponding alternative route in accordance with certain of the received digits and then to cause said register sender to control said switches in accordance with said determination, thereby to extend a connection from said station over said direct route or said alternative route, and means effective only if one of the received digits is of any of certain predetermined values for controlling said last means to prevent the extension of said connection over said alternative route.

11. In a telephone system having trunk lines arranged in direct and alternative routes, a calling station, automatic switches over which said trunk lines are accessible to said station, a register sender for controlling said switches, means for transmitting call-directing digits from said station to control said register sender, means associated with said register sender effective first to determine the condition of trunk lines in a particular direct route and the corresponding alternative route in accordance with certain of the received digits and then to cause said register sender to control said switches in accordance with said determination, thereby to extend a connection from said station over said direct route or said alternative route, and means effective only if one of the received digits is of any of certain predetermined values for causing said second means to arbitrarily assume a predetermined condition of said alternative route irrespective of the true condition of the same.
